UNITED STATES PATENT OFFICE.

ALBERT J. THORNLEY, OF PAWTUCKET, RHODE ISLAND, ASSIGNOR TO NARRAGANSETT MACHINE COMPANY, OF PAWTUCKET, RHODE ISLAND, A CORPORATION OF RHODE ISLAND.

LOCKER SYSTEM FOR GYMNASIUMS.

1,087,850.

Specification of Letters Patent. Patented Feb. 17, 1914.

Application filed July 27, 1912. Serial No. 711,846.

To all whom it may concern:

Be it known that I, ALBERT J. THORNLEY, a citizen of the United States, residing at Pawtucket, in the county of Providence and 5 State of Rhode Island, have invented a new and useful Improvement in Locker Systems for Gymnasiums, of which the following is a specification.

This invention relates to certain new and 10 useful improvements in locker systems for gymnasiums, and the object of the invention is to provide a system of lockers which economizes space and reduces the cost of 15 locker installation, and in which only sufficient dressing lockers are provided for the current need of the members, while still providing an individual box locker for each member, in which box locker the member may keep, under lock and key, his gymna- 20 sium clothing and the like.

In the drawings: Figure 1 is a perspective view of a box locker section. Fig. 2 is a similar view of a dressing locker section. Fig. 3 is a view similar to Fig. 2 of 25 a dressing locker section in which the dressing lockers are of but half the size of those shown in Fig. 2, and Figs. 4 and 5 are top plan views partly in section of the dressing rooms of a gymnasium, showing the manner 30 in which the system is carried into practice.

It is well known that the individual lockers at present commonly used in gymnasiums are actually used only from two to six hours each week, and the lockers are much 35 larger than necessary for the storage of the gymnasium clothing, consequently space is wasted.

In accordance with the present invention each member is given a box locker shown in 40 Fig. 1 at 1, each box locker being equipped with a padlock 2. The box lockers are only of sufficient size to receive the gymnasium clothing of the members and are only about one-sixth the size of the usual dressing lockers 3 depicted in Fig. 2. In Fig. 2 the dressing lockers 3 are provided with hasps 4 that are adapted to receive the padlocks of the 45 lockers 1. In Fig. 3 of the drawings the individual dressing lockers are only one- 50 half the size of those shown in Fig. 2 and have hasps 4 to receive the padlocks 2. The smaller dressing lockers of Fig. 3 are for use in gymnasiums where the dressing room

space is small, or where economy in installation is desired or where the dressing lockers are to be used by boys.

It will be understood that the proportion of dressing lockers to the number of box lockers is determined by the number of the membership of the gymnasium that attend 60 at one time. Thus in Fig. 4 of the drawings the proportion of box lockers to the number of dressing lockers is about six to one, while in Fig. 5 the proportion is about 65 nine to one.

In accordance with the present system each member is given a box locker 1 and a key for the padlock 2 thereof. The dressing lockers 3 are unprovided with padlocks, that is to say, they are normally open, and 70 are only closed when a member enacts the following procedure: A member coming to exercise, removes the padlock from his box locker 1, takes out his effects and carries them with his padlock to any one of the 75 dressing lockers 3 which happens to be vacant. The member then dons his gymnasium suit and places his street clothes in the dressing locker 3 and locks the same with his padlock 2 that he has brought 80 from his box locker. After exercising he returns to the dressing locker 3 that contains his clothes, opens the same by removal of the padlock, dons his street clothing, and carries his gymnasium effects to his 85 box locker, and puts said effects in his said box locker and locks it. Thus the dressing locker 3 that he has used has been left open by him, enabling the same to be used by another member. When the member has 90 returned his gymnasium effects to the box locker 1 and has locked same, the locking operation automatically sets a "use" signal 95 5. The laundryman unlocks the box lockers in sections by means of a lever 6 and removes the soiled clothes and towels and puts the dry, clean, sterilized clothing and towels in the box locker ready for use when the member again returns to the gymnasium for exercises.

From the above it will be apparent that the dressing lockers which are of less number than the box lockers and which occupy so much room, are normally open and unoccupied, while the box lockers which hold 105 the effects of the individual members and

which occupy comparatively little space, effect a saving, not only in the cost of installation, but further in the space required.

Having thus described my invention, I claim as new and desire to secure by Letters Patent;—

1. A locker system for gymnasiums comprising one series of lockers adapted to store the gymnasium effects of the members and approximating in number the number of members and another series of lockers approximating in number the number of members likely to be using the gymnasium at any one time and larger in size than the first named lockers and adapted to hold the street effects of the members, the number and size of the larger lockers being such in relation to the number and size of the smaller lockers that the space occupied by the entire locker system is substantially less than would be required by a single set of lockers each of the size of the larger lockers and equal in number to the number of the smaller lockers.
2. A locker system for gymnasiums comprising one series of lockers adapted to store the gymnasium effects of the members and approximating in number the number of members and another series of lockers approximating in number the number of members likely to be using the gymnasium at any one time and larger in size than the first named lockers and adapted to hold the street effects of the members, the number and size of the larger lockers being such in relation to the number and size of the smaller lockers that the space occupied by the entire locker system is substantially less than would be required by a single set of lockers each of the size of the larger lockers and equal in number to the number of the smaller lockers.

locker system is substantially less than would be required by a single set of lockers each of the size of the larger lockers and equal in number to the number of the smaller lockers, and locking means for each smaller locker for normally locking same and being removable therefrom to enable the locking means to be applied to any one of the larger lockers when a member removes his gymnasium effects from the smaller locker that has been assigned to him and places his street effects in one of the larger lockers.

3. A locker system for gymnasiums comprising one series of normally locked lockers adapted to store the gymnasium effects of the members and approximating in number the number of members, and another series of normally open lockers larger in size, adapted to hold the street effects of the members and approximating in number the number of members likely to be using the gymnasium at any one time, the number and size of the larger lockers being such in relation to the number and size of the smaller lockers that the space occupied by the entire locker system is substantially less than would be required by a single set of lockers each of the size of the larger lockers and equal in number to the number of the smaller lockers.

In testimony whereof I have signed my name to this specification in the presence of two subscribing witnesses.

ALBERT J. THORNLEY.
